United States Patent

Des. 237,054
Patented Oct. 7, 1975

237,054

PACKAGING CONTAINER OR THE LIKE

Ernest L. Smith, Kansas City, Mo., assignor to Phillips
Petroleum Company, Bartlesville, Okla.

Filed Nov. 1, 1972, Ser. No. 302,878

Term of patent 14 years

Int. Cl. D9—03

U.S. Cl. D9—216

FIG. 1

FIG. 3

FIG. 1 is a front elevational view of a packaging container or the like showing my new design, the rear elevational view being the same except for the omission of the vertical seam line;

FIG. 2 is a side elevational view thereof, the opposite side being the same; and

FIG. 3 is a top plan view thereof.

I claim:

The ornamental design for a packaging container or the like, as shown and described.
